UNITED STATES PATENT OFFICE.

HERMAN LISSNER, OF NEW YORK, N. Y.

TAG FOR CLOTHING.

Application filed February 12, 1925. Serial No. 8,723.

To all whom it may concern:

Be it known that HERMAN LISSNER, a citizen of the United States, residing at New York, in the county of New York and State of 5 New York, has invented certain new and useful Improvements in Tags for Clothing, of which the following is a specification.

This invention relates to new and useful improvements in tags or tickets which may 10 be readily and quickly attached to and disconnected from a button on a garment or other article, without employing any other medium, the tag being of a self-locking character.

15 Another important object of the invention resides in the provision of a tag which will displace the present general method of sewing tags which show sizes, prices and other items, to such articles as clothing.

20 With these and other objects in view, my invention consists in the novel features of construction, combination and arrangement of parts as will be hereinafter referred to and more particularly pointed out in the 25 specification and claims.

In the accompanying drawing, forming a part of this application,—

Figure 1 is a plan view of my invention showing the tag attached to the button on a 30 garment which is broken away;

Figure 2 is a section on line 2—2 of Fig. 1;

Figure 3 is a perspective view of the tag; and

Figure 4 is a perspective view of a roll of 35 tags before being separated.

In describing the invention I shall refer to the drawing, in which similar reference characters designate corresponding parts throughout the several views, and in which 40 the tag 1 has a circular opening 2 provided near the top thereof. From this circular opening 2, two diverging slits 3 are formed which run downwardly and outwardly and then curve inwardly as shown at 4.

45 The inwardly curved ends of the slits designated at 4 terminate at points designated at 5 in the drawing. These slits form an upwardly tapered tab or the like 6, which when slightly displaced outwardly allows 50 the button 7 of a garment 8 to be inserted through the space between the slits 3. When the tag is drawn downwardly over the button thus inserted, the shank, designated in the drawing as 10, which is formed by the 55 threads securing the button to the garment,

will enter the opening 2 in the tag. The button may then be tilted and the upper end of the tab 6 disposed under said button. The formation of the opening 2 and the intersection of the slits 3 therewith provides 60 the upper end of the tab 6 obviously with an arcuate portion, designated in the drawing at 9. After the button has been tilted as described above so that the tab is disposed therebelow, this arcuate portion 9 is adapted 65 to partially encircle the shank 10 and lock the tag in place on the garment. Thus the circular opening 2 with the portion thereof forming the curved end 9 of the tab forms substantially a self-locking means for the tag 70 when the latter is applied to the garment as above described.

The curving of the slits inwardly, as shown by the numeral 4, obviously forms a safeguard to prevent the possibility of 75 tearing the slits when the tab is displaced for the insertion of the button through the space formed by the slits 3.

In Figure 4 I have shown the tags 1 formed in strips, which strips may be of any 80 desired length and preferably of such length as to be formed into rolls. Such manufacture of the same has been found to be most economical and convenient in shipment, as well as in actual use. Further by providing 85 the tags in strips, openings and slits may be formed in a large number of the same through a single operation, thus economizing in labor and expense in the manufacture thereof. 90

From the foregoing description of the construction of my improved device, it will be seen that I have provided a simple, inexpensive and efficient means for carrying out the objects of the invention, and while I have 95 particularly described the elements best adapted to perform the functions set forth, it is obvious that various changes in form, proportion, and in the minor details of construction may be resorted to, without departing from the spirit or sacrificing any of the principles of the invention. 100

Having thus described my invention, what I claim is:—

1. A tag having an opening therein and 105 provided with a pair of slits diverging downwardly from said opening to provide a tab, the lower ends of said slits being curved inwardly toward one another to prevent the tearing of said slits to the outside edges 110

when the tab is displaced from the body to receive the shank of a button in said opening.

2. A tag having an opening therein and provided with a pair of slits diverging downwardly from said opening, said slits being formed on straight lines for the greater portion of their length and having their lower ends curved inwardly toward one another to form decided and short arc portions thereon, whereby to prevent the tearing of said slits to the outside edge when the tab is displaced from the body of the tag.

3. As an article of manufacture, a tag

having an opening therein and formed with 15 a pair of slits diverging downwardly from said opening, said slits being straight for the greater portion of their length and having the lower ends thereof curved inwardly toward one another to form decided and short 20 arc portions thereon, the formation of said slits providing substantially a heart-shaped tab therebetween and the arc portions on said slits tending to prevent tearing of the latter to the outside edges thereof when the 25 tab is displaced with respect to the tag.

In testimony whereof I affix my signature.
HERMAN LISSNER.
